UNITED STATES PATENT OFFICE.

TOMPSON PAXSON REED, OF LONG BEACH, CALIFORNIA.

RAILWAY-SWITCH.

1,129,015.

Specification of Letters Patent. Patented Feb. 16, 1915.

Application filed April 17, 1913. Serial No. 761,848.

To all whom it may concern:

Be it known that I, TOMPSON P. REED, a citizen of the United States, and resident of Long Beach, in the county of Los Angeles and State of California, have invented certain new and useful Improvements in Railway-Switches, of which the following is a specification.

The invention relates to improvements in railway switches of that type which are automatically operated by mechanism on a car.

The object of the present invention is to equip the track with simple and comparatively inexpensive switch mechanism, and to provide a simple, practical, and efficient construction, adapted to be readily applied to a car, and which will be under the control of the motorman of a street railway car or the engineer of a locomotive, for positively operating the switch.

With these and other objects in view the invention consists in the construction and novel combination of parts hereinafter fully described, illustrated in the accompanying drawing, and pointed out in the claims here-to appended, it being understood that various changes in the form, proportion, size and minor details of construction, within the scope of the claims, may be resorted to without departing from the spirit or sacrificing any of the advantages of the invention.

In the drawing: Figure 1 is a plan view of a railway switch constructed in accordance with this invention. Fig. 2 is a plan view of a street car truck equipped with car mechanism constructed in accordance with this invention. Fig. 3 is a plan view of a portion of a truck provided with car mechanism designed for use on a locomotive. Fig. 4 is a plan view of the truck shown in Fig. 3 and a portion of the track mechanism, and illustrating the manner of actuating the latter. Fig. 5 is a side elevation of a portion of a street car provided with switch controlling mechanism constructed in accordance with this invention.

Like numerals of reference designate corresponding parts in all the figures of the drawing.

In the accompanying drawing, in which is illustrated the preferred embodiment of the invention, the railway track is equipped with switch rails 8 connected by cross braces 6 and 7 which maintain the switch rails in

transverse alinement. The cross brace 7 is provided with a rear extension 9, which is pivoted at 10 to one of the cross ties, and in the operation of the switch, the pointed ends of the switch rails move laterally a limited distance, the switch rails 8 swinging on the pivot 10, so that one or the other of them will contact with one of the main rails 11 and 12. The cross brace 6, which is located near the pointed ends of the switch rails, is pivotally connected at 14 midway between the switch rails to one end of a longitudinally disposed track lever 13, which is ful-crumed intermediate of its ends at 15 to one of the cross ties. The other or free end of the lever 13 is provided with an upwardly projecting antifriction roller 16, adapted to be engaged by car mechanism hereinafter described, to move the switch lever laterally from one side to the other. When the lever 13 is engaged and actuated by the car mechanism, the switch rails 8 are correspondingly thrown to one side or to the other.

No claim is made in the present application to the construction of the track device.

The car mechanism comprises in its construction a longitudinally disposed, horizontally swinging switch operating arm 18, secured at its inner or rear end to a plate 19 which is pivoted at 24 to the underside of a cross bar 20 of a car truck 17. The switch operating arm tapers forwardly, its front end being pointed and the said arm having an enlarged body portion at the pivot 24 of the plate 19. The plate 19, which extends across the truck, is provided in its ends with recesses 19^a, receiving projecting stops 20^a of the cross bar 20. The stops 20^a are adapted to engage the end walls of the recesses 19^a to limit the oscillatory movement of the pivoted plate and the switch operating arm 18.

In order to bring the arm of the switch operating arm 18 within the control of the motorman, the pivoted plate 19 is equipped with a substantially L-shaped arm 21, provided at its inner or rear end 22 with an attaching portion which is secured to a forward extension of the pivoted plate 19. The L-shaped arm 21, which extends upwardly and forwardly, carries at its outer or front end a toothed rack or segment 23 of the plate 19 and the switch operating arm 18, and meshing with a pinion 26 of a vertical operating shaft 25. The vertical operating shaft 25 is journaled in suitable

bearings on the car and it extends through the platform thereof. The pinion 26, which is suitably secured to the lower end of the shaft 25, is arranged beneath the platform of the car. The upper end of the vertical shaft 25 is provided with a crank handle 27, by means of which the shaft may be turned to rotate the pinion and oscillate the arm 21. Any suitable means may be provided at the 10 crank for holding the same in such position that the arm will be in parallelism with the rails 11 and 12, or in such other position as may be necessary to move the switch rails either to the right or to the left.

15 It is obvious that the car or truck mechanism may be used on an engine, cab, or tender of a locomotive, in which case the pivoted plate 29 may, as illustrated in Figs. 3 and 4 of the drawing, be provided with a 20 rear extension 30, to which is pivoted a longitudinally disposed arm of a substantially T-shaped lever. This T-shaped lever, which is provided with transversely disposed arms 34, is pivoted centrally of the 25 same at 32 to the truck, and a connecting rod 33 may be attached to either or both of the laterally extending arms 34. Through the connecting rod 33 the engineer is enabled to set the mechanism to throw the 30 switch.

What is claimed is:—

1. A switch including car mechanism

comprising a pivoted transversely disposed plate movable in a horizontal plane and provided in its ends with recesses, fixed stops 35 extending into the recesses and arranged to be engaged by the end walls thereof for limiting the pivotal movement of the said plate, a switch operating arm carried by and extending from the plate, and operating mechanism connected with the plate for actuating the same.

2. A switch including car mechanism comprising a horizontally movable pivoted plate, an arm extending from the plate and provided with a toothed rack, an operating shaft having a pinion meshing with the rack, and a switch operating arm extending from and carried by the pivoted plate.

3. A switch including car mechanism 50 comprising a pivotally mounted horizontally movable switch actuating arm, a toothed rack connected with the arm, a pinion meshing with the rack, and an operating shaft connected with the pinion for swing- 55 ing the arm.

Signed at the city of Long Beach county of Los Angeles State of California, this 10th day of April, 1913, in the presence of witnesses.

TOMPSON, PAXSON, REED.
